(57) **CLAIM**

(**) Term: **14 Years**

The ornamental design for a lid for container with rotatable reclosable spout, as shown and described.

(21) Appl. No.: **29/490,810**

DESCRIPTION

(22) Filed: **May 13, 2014**

FIG. 1 is a perspective view of the top, right, and front side of

(51) **LOC (10) Cl.** 09-07

FIG. 2 is a front side elevation view of the lid for container

(52) **U.S. Cl.**

with rotatable reclosable spout shown in FIG. 1;

USPC **D9/449**; D7/392.1

FIG. 3 is a back side elevation view of the lid for container

(58) **Field of Classification Search**

with rotatable reclosable spout shown in FIG. 1;

USPC D9/435, 436, 438, 440, 443, 447, 449,
D9/453, 454; D7/392.1, 396.2

FIG. 4 is a right side elevation view of the lid for container

CPC B65D 41/04; B65D 51/00

with rotatable reclosable spout shown in FIG. 1;

See application file for complete search history.

FIG. 5 is a left side elevation view of the lid for container with

(56) **References Cited**

rotatable reclosable spout shown in FIG. 1;

U.S. PATENT DOCUMENTS

FIG. 6 is a top side plan view of the lid for container with
